UNITED STATES PATENT OFFICE

FREDERICK G. HAUCK, OF CHICAGO, ILLINOIS, ASSIGNOR TO PABST CORPORATION OF MILWAUKEE, WISCONSIN, A CORPORATION OF WISCONSIN

DESIGN FOR A CARTON OR SIMILAR ARTICLE

Application filed May 9, 1932. Serial No. 43,752. Term of patent 14 years.

To all whom it may concern:

Be it known that I, FREDERICK G. HAUCK, a citizen of the United States, residing at Chicago, in the county of Cook and State of Illinois, have invented a new, original, and ornamental Design for a Carton or Similar Article, of which the following is a specification, reference being had to the accompanying drawing, wherein

Figs. 1 and 2 represent perspective views of such carton from two different points of view.

I claim:

An ornamental design for a carton or similar article, as shown.

FREDERICK G. HAUCK.
